(57) CLAIM

(21) Appl. No.: 29/331,216

The ornamental design for scoreboard in the form of a city seal, as shown and described.

(22) Filed: Jan. 21, 2009

DESCRIPTION

(51) LOC (9) Cl. 21-01

FIG. 1 is a front view of a scoreboard in the form of a city seal showing our new design;

(52) U.S. Cl. D10/46.1

FIG. 2 is a side view thereof;

(58) Field of Classification Search D10/46.1,

FIG. 3 is another side view thereof;

D10/46; D21/324, 333, 606, 780, 781, 788,

FIG. 4 is a top view thereof; and,

D21/789; 116/222-225, 173-175, DIG. 1,

116/DIG. 3; 235/1 B; 446/268

FIG. 5 is a bottom view thereof.

See application file for complete search history.

The broken lines showing the environment are for illustrative purpose only and form no part of the claimed design.
